DESIGN FOR A LIQUID FEEDING NOZZLE

Hettie R. Pullen, Glenmore, La.

Application June 26, 1941, Serial No. 101,708

Term of patent 7 years

To all whom it may concern:

Be it known that I, Hettie R. Pullen, a citizen of the United States, residing at Glenmore, in the parish of Rapides and State of Louisiana, have invented a new, original, and ornamental Design for a Liquid Feeding Nozzle, of which the following is a specification, reference being had to the accompanying drawing, forming part thereof.

Figure 1 is an elevational view of a liquid feeding nozzle showing my new design.

Figure 2 is an elevational view taken at right angles to Figure 1, and

Figure 3 is a top plan view thereof.

I claim:

The ornamental design for a liquid feeding nozzle, as shown.

HETTIE R. PULLEN.
